UNITED STATES PATENT OFFICE.

FRANKLIN B. KENDALL, OF TUMWATER, WASHINGTON TERRITORY, AS
SIGNOR TO HIMSELF, GEORGE GELBACH, OF SAME PLACE, AND ROYAL
S. WESTERN, OF OLYMPIA, WASHINGTON TERRITORY.

WINDMILL.

SPECIFICATION forming part of Letters Patent No. 398,054, dated February 19, 1889.

Application filed January 6, 1888. Serial No. 259,954. (No model.)

To all whom it may concern:

Be it known that I, FRANKLIN B. KENDALL, of Tumwater, in the county of Thurston and Territory of Washington, have invented a
5 new and Improved Windmill, of which the following is a full, clear, and exact description.

The object of my invention is to provide a new and improved windmill in which the
10 wind-wheel is turned out of the wind automatically as soon as the wind blows with more than the normal pressure.

The invention consists of rods connected with the spokes of the wind-wheel and with
15 a sliding rod operating on a drum carrying the vane.

The invention also consists of certain parts and details and combinations of the same, as will be fully described hereinafter, and then
20 pointed out in the claims.

Reference is to be had to the accompanying drawings, forming a part of this specification, in which similar letters of reference indicate corresponding parts in all the figures.

25 Figure 1 is a sectional elevation of my improvement. Fig. 2 is a plan view of the same, parts being in section. Fig. 3 is a rear end elevation of parts of my improvement with the vane removed. Fig. 4 is a perspective view of one of the wind-wheel arms, and Fig. 5 is an enlarged sectional plan view of the sliding rod and its connections on the line $x-x$ of Fig. 1.

35 My improved windmill A is provided with a suitably-constructed tower, B, in which is mounted to rotate the vertical hollow shaft C, provided near its lower end with a bevel gear-wheel, D, meshing into a bevel gear-wheel, D', secured to the driving-shaft D²,
40 connected in any suitable manner with the machinery to be driven. Near the upper end of the hollow main shaft C is held to rotate a frame, E, on which is mounted the wind-wheel F and the vane G.

45 The wind-wheel F is secured on a hollow shaft, H, mounted to rotate in a bearing, E', secured on the frame E; and on the inner end of said hollow shaft H is secured a bevel gear-wheel, H', meshing into a bevel gear-wheel,

H², secured to the upper end of the main hollow shaft C. The wind-wheel F is provided with a suitable number of radial spokes, I, held between flanges H³, formed on the hollow shaft H. On the front and rear of the flanges H³ are secured short spokes J, provided at their sides next to the spokes I with inclines J', as illustrated in Fig. 1. Bolts pass through the flanges H³, the spokes I, and the spokes J, thus securing the parts firmly together. The spokes J extend only a short distance outward in line with the spokes I, so that when the latter are bent inward or outward a suitable distance they rest against the inclines J' of the said spokes J, thus preventing a further bending of said spokes I.

50 Each spoke I of the wind-wheel F carries a number of blades, K, increasing in length toward the outer end of the wheel and extending in a straight line at one end and in an inclined line at the other end, as illustrated in Figs. 1 and 4. A small space intervenes between two successive blades, K, and the spokes I may be connected with each other at their outer ends, if deemed necessary. In front, near the upper end of each spoke I, is secured an eye, I', connected with one end of an inclined rod, L, extending radially and outward from the wheel F, and having its inner end formed into an eye, L', engaging a ring, N', held on a block, N, secured to the outer end of a rod, O, passing through the hollow shaft H. The block N is provided with grooves N², into which fit the eyes L' of the rods L, so as to prevent said rods L from being displaced on the block N, as is fully shown in Fig. 5.

55 The inner end of the rod O is provided with a ball, O', fitted loosely into a cavity, P', formed in a slide, P, reciprocating in axial line with the wheel F in a suitable guide, Q, secured to the frame E. The cylinder P' is nearly filled with oil, against which operates the ball O'. On one end of the slide P is secured one end of a rope, R, extending to and wound around a drum, S, secured to a vertical shaft, T, mounted to rotate in a suitable oil-box, E², fastened on the frame E. On the vertical shaft T and on the drum S is secured

the radial forked arm G' of the vane G, which latter thus turns with the vertical shaft T and with the said drum S. On the other end of the slide P is secured one end of a rope, R', also passing over and wound around the drum S, in an opposite direction, however, from the rope R. It will be seen that when the slide P moves forward or backward one rope, R or R', is unwound from the drum S, while the other rope is wound on the drum. On the drum S is also fastened one end of a rope, U, which passes over a pulley, U', secured to the frame E, and then the rope U extends downward and carries on its lower end a weight, U², for counterbalancing the vane G. Another rope, V, is wound and secured by one end on the drum S in an opposite direction to the rope U and passes over a pulley, V', held in suitable bearings on the frame E above the upper opening of the hollow shaft C, and carries on its lower end a weight, V², which can be drawn downward by a lever, W, mounted on the tower B.

The operation is as follows: The vane G is held in position by the counterbalancing-weights U² and V², so that the wind coming in any direction acts on the vane G, and thus turns the frame E according to the direction of the wind, whereby the wind-wheel F is thrown in the wind. The latter acts on the blades K of the wheel F in the usual manner, and thereby rotates the wind-wheel F, so that its shaft H, by means of the bevel gear-wheels H' and H'', imparts a turning motion to the main hollow shaft C, connected in any suitable manner with the machinery to be driven. If the wind increases beyond a normal pressure, the force of the wind causes a backward bending of the spokes I, so that the rods L exert a pressure against the block N in the direction of the arrow a', whereby the rod O is moved inward and causes the slide P to slide in the same direction in its guide Q. This inward sliding of the slide P rotates the drum S by means of the rope R', which exerts a pull on the drum S, so that the vane G, secured to the said drum, is held in position by the force of the wind, thereby causing, on account of the said movement of the drum, the wheel F to move out of the wind, so that the speed of the wind-wheel is decreased. As soon as the pressure of the wind moderates, the spokes I again spring forward and assume their normal position, whereby the rod O is caused to slide outward in the inverse direction of the arrow a', thereby pulling the slide P to its normal position and again rotating the drum S until the vane G is again in a parallel line with the axis of the wind-wheel F. Whenever the operator desires to throw the wind-wheel out of the wind, he presses the lever W downward, so as to pull the rope V in the same direction, thereby exerting a pull on the drum S and causing the frame E to swing, so as to throw the wheel F out of the wind. The vane G then assumes an inclined position in relation to the axis of the wind-

wheel F. Thus it will be seen that the position of the vane G is regulated according to the force of the wind—that is, by the bending of the spokes I of the wind-wheel F. When a back wind strikes the wind-wheel F, then the spokes are bent forward until they rest against front spokes, J, thus preventing a breaking of the said spokes. 75

Having thus described my invention, I claim as new and desire to secure by Letters Patent—

1. In a windmill, the combination, with a wind-wheel provided with spokes carrying blades, of rods connected with said spokes, a sliding rod connected with said rods, and a vane connected with said sliding rod, substantially as shown and described. 80

2. In a windmill, the combination, with inclined rods connected with the spokes of the wind-wheel, of a sliding rod connected with the said inclined rods and passing through the shaft of the wind-wheel, a drum connected by ropes with the said sliding rod, and a vane held on the said drum, substantially as shown 90 and described.

3. In a windmill, the combination, with a wind-wheel consisting of a hollow shaft supporting spokes carrying blades, of spokes having inclined faces and held in the front and rear of said wind-wheel spokes, rods secured to the outer ends of said wind-wheel spokes and extending in front of the wind-wheel in an inclined position, a block in which the inner ends of said rods are secured, and a rod carrying said block and passing through said hollow shaft, being connected with the tail-vane, substantially as shown and described. 95 100

4. In a windmill, the combination, with a sliding rod, of ropes connected with the said sliding rod, a drum on which said ropes are wound, a vane secured to the said drum and turning with the same, and a second set of ropes connected with said drum and carrying counterbalance-weights, substantially as 105 110 shown and described.

5. In a windmill, the combination, with a hollow main shaft and a frame turning on the same, of a wind-wheel having a hollow shaft mounted on the said frame and connected 115 with the said main shaft, rods connected with the upper ends of the spokes of said wind-wheel, a block in which the inner ends of said rods are fastened, a sliding rod carrying the said block and passing through the hollow shaft of the wind-wheel, a slide held on the inner end of said sliding rod and mounted in a suitable guide, ropes connected with the ends of said slide, a drum mounted on a vertical shaft and carrying the said ropes, and a 120 125 counterbalanced vane held on said drum, substantially as shown and described.

6. In a windmill, the combination, with a hollow main shaft and a frame turning on the same, of a wind-wheel having a hollow shaft mounted on said frame and connected with said main shaft, rods connected with the upper ends of the spokes of the said wind-wheel, a block on which the inner ends of said rods

are fastened, a sliding rod carrying the said block and passing through the hollow shaft of the wind-wheel, a slide held on the inner end of said sliding rod and mounted in a suitable guide, ropes connected with the ends of said slide, a drum mounted on the vertical shaft and carrying said ropes, a counterbalanced vane held on said drum, counterbalance-weights connected with said drum, and

spokes secured to the hollow shaft of the wind-wheel and adapted to limit the bending of the spokes of the wind-wheel, substantially as shown and described.

FRANKLIN B. KENDALL.
